FEELER MECHANISM FOR LOOMS.

1,369,490.

Specification of Letters Patent. Patented Feb. 22, 1921.

Application filed April 5, 1920. Serial No. 371,301.

To all whom it may concern:

Be it known that I, MELVIN L. STONE, a citizen of the United States, residing at Lawrence, county of Essex, and State of Massachusetts, have invented an Improvement in Feeler Mechanisms for Looms, of which the following description, in connection with the accompanying drawings, is a specification, like characters on the drawings 10 representing like parts.

This invention relates to feeler mechanisms for looms, through the agency of which replenishment of filling is effected when that in the shuttle becomes substantially exhausted, and prior to complete exhaustion.

The feeler mechanism of the present invention is of that general type wherein there is an impinging and a penetrating 20 portion. The feeler has projecting therefrom a spring which constitutes the impinging element, and which is elongated in a direction longitudinally of the shuttle by the frontward pressure exerted upon the spring 25 on each detecting beat when a working supply of filling is present in the shuttle. The penetrating portion is constituted as a finger or fingers which project from the feeler approximately to the same extent as the impinging surface of the spring, so that on 30 each detecting beat, when a working supply of filling is present, the penetrating portion or finger will enter the mass of filling and permit the advancing filling to engage the 35 impinging spring and elongate it. When, however, the filling has become substantially exhausted on a detecting beat, the penetrating portion or finger will engage the surface of the bobbin and consequently the advancing 40 lay will not effect functional impingement of the filling or filling carrier against the spring to elongate it. Advantage is taken of this condition of affairs to effect 45 replenishment of filling in the shuttle when the impinging spring fails to be elongated by the frontward pressure on a detecting beat.

The impinging spring and the penetrating finger or fingers constitute the tip portion 50 of the feeler, and, in the present invention, the impinging spring is preferably of the leaf character having a bend which projects rearwardly from the feeler. One portion of the leaf spring is secured to the end of the 55 feeler, and the other portions of the spring are permitted to move in a direction longi-

tudinally of the shuttle when the bend in the spring is deflected by frontward pressure upon it. The spring is operatively related to a controller which, when the impinging 60 spring fails to be elongated in a direction longitudinally of the shuttle, effects replenishment of filling through a train of mechanism.

In the accompanying drawings:— 65

Figure 1 is a plan view showing the action of the feeler mechanism when, on a detecting beat, a working supply of filling is present in the shuttle;

Fig. 2 is a similar view, showing the action of the feeler mechanism when the filling is substantially exhausted on a detecting beat;

Fig. 3 is an enlarged detail of the feeler type constituted by the impinging spring and the penetrating finger or fingers; and 75

Fig. 4 is a perspective view of the improved feeler mechanism looking from the rear.

The feeler is supported for movement toward and from the front of the loom. This 80 may be effected in various ways, but in the present instance of the invention, the feeler itself is mounted for reciprocating movement in a feeler stand, and carries an actuator which, when the filling is substantially 85 exhausted, is placed in a position to move a train of mechanism as the feeler moves frontwardly, to effect replenishment of filling.

The feeler stand 1 may be appropriately 90 secured to the loom frame or bracket connected thereto, as is usual, by means of the securing screws 2 which pass through a slot 3 formed in a flanged portion of the feeler stand. The feeler stand 1 has mounted 95 thereon for reciprocating movement toward and from the front of the loom, the feeler 4, the front portion of which is formed as a stem or rod 5 which is surrounded by a spring 6 within the feeler stand, one end of 100 the spring resting upon a shouldered portion 7 of the feeler and the other end of the spring against the inner surface 8 of the feeler stand, the construction being such that the spring 6 normally holds the feeler in its 105 rearward feeling position and returns it to such feeling position after having been displaced frontwardly.

Mounted on the feeler is the actuator 9 which, in the present instance of the invention, is pivoted to the feeler at 10 and has a frontwardly-extending portion provided 110

with a fan-tail end 11 which at times may be positioned to engage a transmitter 12 for positioning a train of mechanism for replenishment of filling. The fan-tail end 11 of the actuator is normally under the influence of a yielding and lifting pin 13 of usual construction, which tends to move the fan-tail end of the actuator into a path of non-intersection with the transmitter 12 as the 10 feeler moves forwardly. The transmitter 12 is guided in its movement by the guide opening 14 formed as a part of or connected to the feeler stand.

Adjustably connected to the rearward end 15 portion of the actuator 9 a short distance above its pivotal connection 10 with the feeler, is a roller 15 mounted upon an adjusting screw 16 which may be held in adjusted position by a set nut 17.

20 The tip of the feeler 4 is formed of an impinging and a penetrating portion. The impinging portion in the present instance comprises a spring 18 having a bend or bulge 19. The spring 18 is secured to the end of the 25 feeler preferably at one end of the spring, and its other end is permitted movement longitudinally of the bobbin by the forward pressure upon the bend 19 on a detecting beat. As shown, the end 20 of the impinging 30 spring 18 is secured to the feeler by a pin 21 which passes through the end of the spring and has a pointed projecting end portion 22 which constitutes one element of the penetrating portion of the feeler. The 35 spring 18 is provided with a slot 23 at the opposite side of the bend 19 through which passes the pin 24 which, like the pin 21, is provided with a pointed exposed portion 25 for penetrating the filling when a working 40 supply is present on a detecting beat. The free end portion of the spring 18 is preferably deflected forwardly as indicated in Fig. 3, and is there operatively associated with a controller 26 which, in the present instance, is formed as a lever pivoted at 27 to the feeler 4, and having a forwardly-extending arm 28 provided with a cam portion 29. The rear end portion of the controller 26 may conveniently be passed 45 through an opening on the free end of the spring 18, the construction being such that when the spring 18 is elongated by forward pressure of a working supply of filling upon the bend 19 thereof, the controller 50 26 will be moved about its pivotal support 27 to throw the cam 29 from under the roller 15 connected to the actuator, to thereby permit the yielding pin 13 to raise the fan-tail end of the actuator into inoperative relation 55 with respect to the transmitter 12. During such elongation of the spring by the forward pressure of the bend 19, the slotted portion 23 of the spring is directed by the pin 24 to move in a direction longitudinally 60 of the bobbin.

When on a detecting beat, a working supply of filling is present in the shuttle, the penetrating finger or fingers of which in the present instance there are two, will sink into the mass of filling and permit the forward movement of the filling to impinge upon the bend 19 of the spring and elongate the latter, thereby effecting movement of the actuator into its inoperative position. When, however, the filling is substantially exhausted on a detecting beat, the ends of the penetrating finger or fingers will meet the surface of the bobbin and move the feeler forwardly, so that the bend 19 of the impinging spring is no longer subjected to the deflecting movement by the forward pressure of the filling, and the spring remains substantially in fixed position relative to the end of the feeler. Under these conditions, the cam 29 will not be moved from under the roller 15 of the actuator, and the fan-tail end 11 of the actuator will travel forwardly in a path to intercept the transmitter 12 and effect replenishment of filling.

In the present instance of the invention, the penetrating tip portion of the feeler is shown as formed of two pins, having conically-extending end portions which project rearwardly from the end of the feeler, substantially the same distance as the bend 19 of the spring, but it will be apparent, of course, that the number of penetrating fingers may be varied and also that the character of the bend 19 in the spring may be changed, the essentials being that when a working supply of filling is present in the shuttle, the penetrating portion of the feeler tip will sink into the filling and the bend of the spring will receive the forward impulse of the filling and cause it to be elongated sufficiently, as indicated in Fig. 1. When, however, the filling is sufficiently exhausted on a detecting beat, the end or ends of the penetrating fingers will cause forward movement of the feeler 4 without effecting deflection of the spring by the forward pressure, so that replenishment is called.

The bobbin 30 may be of usual construction, provided with the head 31 and with the usual bobbin-holding reins, but since these features form no essential part of the present invention, a further illustration or description thereof is unnecessary.

What is claimed is—

1. In a feeler mechanism for looms, the combination of a feeler having a spring provided with a bend extending rearwardly, a penetrating finger extending rearwardly from the feeler to penetrate the filling on a detecting beat and permit the filling to exert forward pressure upon the bend of the spring to elongate the spring until substantial exhaustion of filling, and means for effecting replenishment of filling when the 125 130

spring fails to be elongated on a detecting beat.

2. In a feeler mechanism for looms, the combination of a feeler having a spring provided with a bend extending rearwardly and secured to the feeler at one side of the bend, a penetrating finger extending rearwardly from the feeler to penetrate the filling on a detecting beat and permit the filling 10 to exert frontward pressure upon the bend of the spring to elongate the spring until substantial exhaustion of filling, and means for effecting replenishment of filling when the spring fails to be elongated on a detecting beat.

3. In a feeler mechanism for looms, the combination of a feeler, an impinging spring having a rearwardly extending bend which is adapted to be deflected frontwardly to cause elongation of the spring by the frontward pressure of the filling until substantial exhaustion thereof on a detecting beat, and means for effecting replenishment of filling when the bend in the spring fails to 25 be deflected frontwardly.

4. In a feeler mechanism for looms, the combination of a feeler mounted for movement toward and from the front of the loom, and having a penetrating end portion 30 to sink into the filling when a working supply is present on a detecting beat, and a spring impinging end portion which is elongated in a direction longitudinally of the shuttle by the frontward pressure when 35 the penetrating portion sinks into the filling, and means for effecting replenishment of filling when the spring impinging portion fails to be elongated on a detecting beat.

5. In a feeler mechanism for looms, the combination of a feeler mounted for movement toward and from the front of the loom, an impinging spring and a penetrating finger mounted on the feeler and extending rearwardly therefrom to effect elongation of 45 the impinging spring by the frontward pressure on a detecting beat until the filling is substantially exhausted, and means for effecting replenishment of filling when the impinging spring fails to be elongated on a 50 detecting beat.

6. In a feeler mechanism for looms, the combination of a feeler, an impinging spring carried by the feeler and having a bend to receive the impact of the filling on a detecting beat, a penetrating finger mounted on the feeler to sink into the filling and permit the spring to receive the impact thereof and be elongated thereby until the filling is substantially exhausted on a detecting beat, and 55 means for effecting replenishment of filling when the spring fails to be elongated.

7. In a feeler mechanism for looms, the combination of a feeler mounted for movement toward and from the front of the loom, an impinging spring secured to the end of the feeler 60

and adapted to be elongated in the direction of the longitudinal dimension of the shuttle by the frontward pressure on a detecting beat until the filling is substantially exhausted, a penetrating finger secured to the 70 feeler and which engages the bobbin and relieves the spring of the elongating pressure when the filling is substantially exhausted on a detecting beat.

8. In a feeler mechanism for looms, the combination of a feeler mounted for movement toward and from the front of the loom, a spring secured at one end to the end of the feeler and having a bend to receive the impact of the filling on a detecting beat and 80 to be deflected thereby, a penetrating finger secured to the feeler and which engages the bobbin and relieves the bend of the spring from the deflecting pressure when filling is substantially exhausted on a detecting 85 beat.

9. In a feeler mechanism for looms, the combination of a feeler mounted for movement toward and from the front of the loom, a spring secured at one end to the end of 90 the feeler and having a bend to receive the impact of the filling on a detecting beat and to be deflected thereby, a penetrating finger secured to the feeler and which engages the bobbin and relieves the bend of 95 the spring from the deflecting pressure when filling is substantially exhausted on a detecting beat, and a controller which is moved by the spring and causes replenishment of filling when the bend of the spring fails to 100 be deflected on a detecting beat.

10. A feeler provided with a penetrating finger to enter the filling on a detecting beat and also having secured to its rear end a spring provided with an impinging bend 105 which receives the impact of the filling and effects elongation of the spring when a working supply of filling is present on a detecting beat.

11. A feeler provided with a penetrating finger to enter the filling on a detecting beat and also having secured to its rear end a spring provided with an impinging bend which extends rearwardly from the end of 115 the feeler and by the impact of the filling when a working supply is present on a detecting beat effects elongation of the spring.

12. In a feeler mechanism for looms, a feeler having a tip formed of a leaf spring provided with a bend between its ends, 120 means for securing one end of the leaf spring to the feeler, means for guiding the other end of the spring in its movement due to deflection of the bend by frontward pressure, and a penetrating finger extending 125 rearwardly.

In testimony whereof I have signed my name to this specification.

MELVIN L. STONE.
